APPARATUS FOR UPSETTING THE ENDS OF
PACKAGES OF YARNS

Peter A. Meytre, Valdese, N. C.

Application May 21, 1953, Serial No. 356,564

8 Claims. (Cl. 18—8)

1

This invention relates to textile machinery and more especially to an apparatus for upsetting, breaking or crimping yarn which is to be subjected to sizing or dyeing, or bleaching operations after the yarn has been wound into tubular or conical packages or cakes and the like and these packages are usually of cylindrical shape or truncated conical shape. It often happens that the turns of yarn which are wound adjacent the opposite ends of a cylindrical or conical package or cake, are placed under greater tension than the yarn wound about the medial portion of the package. It is evident that sizing solutions or dyes would more easily penetrate the yarns which are wound more loosely than the yarns which are wound tightly such as the yarn portions appearing at opposite ends of the packages of yarn and it often happens that the turns of yarn forming the opposite ends of the cylindrically-shaped or conically-shaped packages would not be fully penetrated by the dyes or sizing solutions with the result that the yarn in each package is not dyed or treated uniformly throughout its length which, in many instances, would necessitate discarding the same.

It is, therefore, an object of this invention to provide apparatus for upsetting the opposite ends of cylindrically or conically-shaped packages of yarn so as to relieve the tension in the yarns at the outer edges of and at the opposite ends of each package so the packages may subsequently be subjected to a dyeing, sizing or any other treating operation wherein the dye or other solution will penetrate the yarns in each package uniformly throughout the package.

It is another object of this invention to provide an apparatus for automatically breaking the opposed ends of cones of yarn which apparatus has a pair of cup-shaped members adapted to move toward and away from each other and to fit over the opposite ends of a cone of yarn, and when they move toward each other they compress the cones of yarn and then means are provided for automatically discharging the crushed cone of yarn when the cup-shaped members are moved apart from each other and a new uncrushed cone of yarn is set between the cup-shaped members.

It is another object of this invention to provide a machine for automatically upsetting, breaking or crimping opposite ends of packages of yarn which comprises two oppositely disposed cup-shaped or concavo-convex members having their concave sides facing each other and with means provided for feeding a package of yarn

5 to a position between the two cup-shaped members and then moving the two cup-shaped members toward each other to engage the opposite compressed ends of the yarn package and to compress the same to thereby break down the tension in the yarns at each end of the package.

10 It is another object of this invention to provide an apparatus of the type above described which is adjustable to accommodate packages of various sizes or lengths of yarn packages.

Some of the objects of the invention having been stated, other objects will appear as the description proceeds, when taken in connection with the accompanying drawings, in which—

15 Figure 1 is an isometric view of the invention; Figure 2 is a top plan view of the apparatus; Figure 3 is a sectional plan view taken immediately below the top in Figures 1 and 2;

20 Figure 4 is an elevation looking at the remote side of Figure 1 with the side panel removed and showing the reciprocable conveyor in lowered, retracted position;

Figure 5 is a vertical sectional view taken along the line 5—5 of Figure 4;

25 Figure 6 is a vertical sectional view taken substantially along the line 6—6 in Figure 4, but showing one of the concave cup members in elevation, and showing the conveyor in raised, retracted position;

30 Figure 7 is a vertical longitudinal section view through the apparatus and taken substantially along the line 7—7 in Figure 6, also showing the conveyor in retracted position;

Figure 8 is an elevation looking at the discharge end of the apparatus with the end plate removed, but showing the conveyor in lowered position;

35 Figure 9 is an isometric view showing the yarn package feeding means, the slide associated therewith and cam means for operating the same, and showing the conveyor in raised, advanced position.

40 Referring more specifically to the drawings, the numeral 10 indicates four angle iron legs to which are secured four angle iron rails 11 at a point between the upper and lower ends of the legs and on which is fixed a supporting plate 12 and the upper ends of the legs have fixed thereto four angle iron horizontal frame members 14 which support a top plate 15. This apparatus is supported on any suitable surface such as a floor 16.

45 Mounted on the plate 12 is a plurality of bearing stands 20 on which a shaft 21 is rotatably mounted in bearing blocks 22 on the upper ends

of the bearing stands 20. An electric motor 24 is also mounted on the table 12, having a pulley 25 mounted on its motor shaft on which a belt 26 is mounted. This belt 26 is mounted on a pulley 27 which is a part of a reduction gear housing 28 which has a shaft 30 extending therefrom on which a plurality of pulleys 31 are mounted on which belts 32 are disposed and which belts are also mounted on pulleys 33 fixed on the shaft 21. This shaft 21 has a pair of conveyor 10 raising cams 35 secured thereon and also has a pair of cup operating cams 36 secured thereon, the table top 15 has a longitudinally extending slot 40 therein in which a reciprocating conveyor 41 is adapted to have movement. This reciprocating conveyor has pockets A, B and C 15 therein formed from sheet metal or they could be cast and integral with the conveyor assembly. The pocket forming members are indicated by reference characters 44 for the end pocket members which are identical but opposite hand, and 45 for the intermediate pocket members which are identical. These pocket members 44 and 45 are secured to a base plate 46 which has an elongated bar 47 integral therewith. A pair of 25 spaced angle bars 48 are secured to the lower surface of the table 15 and on each side of the slot 40 for guiding the bar 47. The bar 47 has extending outwardly therefrom a bolt 50 which has a spacer 51 thereon and the outer end of this bolt 50 is slidably mounted in a slot 52 which is integral with a shaft and guide member 53.

This shaft and guide member 53 are mounted for sliding movement in brackets 54 and the left-hand end of this shaft 53 has a rectangular portion 56 which is adapted to have sliding movement in a guideway 57 which has integral therewith brackets 60 and 61 which are suitably secured to the lower surface of table 15. Suitably secured to the lower surface of the table 15 is a pair of guideways 63 in which are mounted vertically sliding members 64 having a notch in their upper portion fitting the bottom and side of the bar 47 and these plate members 64 have vertical sliding movement in the guide members 63. The lower end of the members 64 have a follower roller 66 mounted therein which is adapted to follow the respective conveyor raising cams 35. The vertically sliding members 64 are normally urged downwardly by tension springs 70 anchored in L-shaped brackets on the vertically sliding members 64 and to a suitable spring perch at the upper ends of frame members 71.

The rectangular portion 56 of the shaft 53 has a pin 74 therein which extends into an elongated slot 75 in the upper end of a lever 76 which is pivoted at its lower end as at 77 to a block 78 mounted on the lower platform 12 and this lever 76 has a cam follower roller 80 intermediate its ends which is adapted to follow the closed cam 78 in cam wheel 82 which is fixed on the shaft 21. The conveyor mechanism is moved upwardly by the cams 35 and is moved longitudinally of the machine by the cam wheel 32 and the lever 76.

Mounted on top of the table 15 are opposed compressing devices and since the two structures are identical except opposite hand, like reference characters will apply. Each of these compressing devices comprises a pair of members 90 and 91 secured to the table top having projecting ribs 92 on their proximate surfaces on which are adapted to slide a member 93 and the member 93 is confined in position by the strap members 94. Each of the members 93 has secured there-

to by any suitable means, a cup holding member 95, each cup holding member 95 having a projection 96 which is suitably secured to the top inner end of the member 93.

This member 95 is penetrated by suitable bolts 97 which secure a resilient concavo-convex cup member or die 98 to the member 95. Each of the members 93 has an elongated slot 100 therein loosely penetrated by a bolt 101 having a handle 102 fixed thereon and this bolt 101 is threadably embedded in a rack 103 which meshes with a segmental gear 104 on the upper end of a lever 105 which is pivoted intermediate its ends as at 106 on a bracket 107 secured to the lower surface of the table top 15. Each of these levers 105 have a follower roller 108 thereon adapted to follow the cup operating cam 36. The lower ends of these levers are hooked as at 110 and each has a tension spring 111 secured thereto, the other ends of which are anchored to the bottom plate 12. From the position shown in Figure 6, the follower rollers 108 are on the low side of the cam and therefore the cups or dies 98 disposed fartherest apart, whereas in Figures 1 and 2 the cups 98 are fully moved towards each other to package crushing position.

Secured to the end of the apparatus is a bracket 115 to which is secured a feeding chute 114 comprising transverse channel members 116 on each of which rests a pair of cut-away angle brackets or members 117 each of which has upright members 118 thereon. The lower ends of the angle members 117 are slidably mounted in the channel members 116 and suitable means, such as bolts 120, penetrate the channel members 116 and the inturned portions of the angle members 117 for adjustably securing the brackets 117 on each side to the channel members 116. The channel members 116 are secured to the brackets 115 by any suitable means such as bolts 123 and the bolts 120 are mounted in suitable slots 124 in the bottom wall of each channel member 116, whereby the angle brackets 117 and associated parts can be moved apart or towards each other to adjust the width of the guideway according to the length of the tubes of yarn.

The upper ends of the members 118 or brackets 117 each has secured thereto a bar 126. Bars 126 serve as guides for the upper portions of the packages of yarn. Suitably secured to the angle portion of angle brackets 117 are elongated guide members or bars 118a and 118b, each bar 118a forming a lower side guide and each bar 118b forming a bottom guide and, with bar members 126 as a top guide, a U-shaped delivery chute is formed upon which tubes of yarn or yarn packages may roll into the reciprocating conveyor 41. Guide members 126, 118a and 118b are secured at their front ends to substantially angle shaped brackets 130 which have a horizontal grooved portion slidably mounted on a fixed rectangular elongated member 131 on the upper surface of the table top 15 and these brackets 130 have elongated slots 132 therein penetrated by bolts 133 embedded in the rectangular member 131 whereby the brackets 130 can be adjusted towards and away from each other along with the uprising brackets 118.

An additional guideway is provided for conducting the tubes of yarn comprising L-shaped brackets 134 which likewise are inverted channel members slidably mounted on elongated rectangular members 135 fixed on the table top 15 and each having a slot 136 therein penetrated by bolt 137 by regulating the brackets 134 on one

side apart from the brackets 134 on the other side of the path of travel of the packages of yarn. The brackets 134 have secured thereto guide bars 138 for guiding the yarn to the pressing cups 98.

After the packages of yarn have had their ends crushed and compressed a suitable guiding chute 139 is provided for guiding the crushed yarn packages off the table top 15 and this comprises L-shaped brackets 140 having guide bars 141 secured thereto and each bracket 140 having a slot 143 therein penetrated by a bolt 144 which is threadably mounted in an elongated rectangular guide member 145 mounted on the table top 15, the members 140 being channel-shaped, as shown.

A start and stop switch 150 is mounted in any suitable location on the machine and has a cable 151 leading from a suitable source of electrical energy, not shown, into the switch 150 and another cable 152, having wires 153 and 154, therein extends to the electric motor 24 to thereby furnish electrical energy to the electric motor 24.

Method of operation

It is to be observed that the package moving apparatus has an oscillatory and reciprocatory movement. In Figure 7, the package carrier or reciprocating carrier 41 having the pockets A, B and C therein moves along the longitudinal slot 40 and in the position as shown in Figure 7 has reached the end of its stroke toward the feeding end of the apparatus and is now ready to advance the packages of yarn one step to place the package in pocket B in position to be operated upon by the upsetting cups 98. While the conveyor mechanism has moved on its way to the right in Figure 7, it will be observed that the cams 35 will be holding the conveyor in its uppermost position and immediately after the yarn package in cup B has been delivered to a point between the crimping cups 98, the cams 36 move to a position where the high sides thereof will move the crimping cups 98 toward each other to crimp that package of yarn under resilient pressure. At this position, the crimping cams 36 continue to move to where their low sides will be engaged by the rollers 108, thus allowing the springs 111 to move the crimping cups 98 away from each other as shown in Figures 6 and 8. Then the lowering cams 35 will be at a point where the rollers 66 will be moved into engagement with the lowest surface of the cams 36 under tension of their springs 70 which will lower the conveyor mechanism 41 to where the pin 50 in Figure 7 will be resting in the lower end of slot 52 and will thus lower the members 44 and 45 to where their top-most points will be below the surface of table 15 and then cam wheel 82 will start movement of the conveyor mechanism 41 back to the left in Figure 7 to the fully reversed position as shown in Figure 7 and then the raising cams 35 will start upward movement of the conveyor mechanism to cause it to return to the position shown in Figure 7 to automatically place packages of yarn which have rolled down the inclined guideway 114 resting on bracket 115 and the crushed package in pocket A will be moved outwardly into the discharge chute 139 having rails 141 and the package in pocket B will be in a position to be crushed. This cycle of operation will continue as long as the machine is in operation.

In the drawings and specification there has been set forth a preferred embodiment of the invention and although specific terms are employed, they are used in a generic and descriptive sense only, and not for purposes of limitation,

the scope of the invention being defined in the claims.

I claim:

1. Apparatus for crushing the ends of packages of yarn comprising a framework, having a flat top portion, an elongated slot in said flat top portion, an oscillating and reciprocating conveyor mounted for movement back and forth in said slot, means for lowering the conveyor to where its uppermost portions are disposed below the table top, means for returning the conveyor to original position, means for elevating the conveyor to engage packages of yarn disposed on the table, means for moving the conveyor and packages of yarn longitudinally of the table, a pair of concavo-convex members mounted for movement toward and away from each other with their concave faces facing each other to thereby engage the opposite ends of a package of yarn simultaneously and to apply pressure to the same to break down the ends of the yarn on the packages.

2. Apparatus for crushing the ends of packages of yarn comprising a framework having a flat top portion, an elongated slot in said flat top portion, an oscillating and reciprocating conveyor mounted for movement back and forth in said slot, means for lowering the conveyor to where its uppermost portions are disposed below the table top, means for returning the conveyor to original position and elevating the conveyor to engage packages of yarn disposed on the table, means for moving the conveyor and packages of yarn longitudinally of the table, a pair of concavo-convex members mounted for movement toward and away from each other with their concave faces facing each other to thereby engage the yarn at the opposite ends of a package of yarn simultaneously and to supply pressure to the same to break down the ends of the yarn on the packages, and means for guiding packages of yarn onto the table and positioning the packages above said slot.

3. Apparatus for crushing the ends of packages of yarn comprising a framework having a flat top portion, an elongated slot in said flat top portion, an oscillating and reciprocating conveyor mounted for movement back and forth in said slot, means for retracting the conveyor to where its uppermost portions are disposed below the table top and returning the conveyor to original position and elevating the conveyor to engage packages of yarn disposed on the table for moving the conveyor and packages of yarn longitudinally of the table, a pair of concavo-convex members mounted for movement toward and away from each other and having their concave faces facing each other to thereby engage the opposite ends of a package of yarn simultaneously and to apply pressure to the same to break down the ends of the yarn on the packages.

4. Apparatus for breaking down or compressing the yarn on the ends of tubular packages comprising a conveyor, means for feeding the packages of yarn to the conveyor, a pair of concavo-convex members disposed on each side of the path of travel of the conveyor, the concave faces of said members being in spaced relation to each other and facing each other, means for actuating the conveyor to move a package of yarn between the concavo-convex members, and means for moving the concavo-convex members toward each other to engage and apply pressure to the opposite ends of the yarn package simultaneously.

taneously and means for ejecting the crushed yarn package from the apparatus.

5. Apparatus for breaking down or compressing the yarn on the ends of tubular packages comprising an oscillating and reciprocating conveyor, means for feeding the packages of yarn to the conveyor, a pair of resilient concavo-convex members disposed on each side of the path of travel of the conveyor, the concave faces of said members being in spaced relation to each other and facing each other, means for actuating the conveyor to move a package of yarn between the concavo-convex members, and means for moving the concavo-convex members toward each other to engage and apply pressure to the opposite ends of the yarn package simultaneously, the conveyor serving as means for ejecting the crushed yarn package from the apparatus.

6. Apparatus for breaking down or compressing the yarn on the ends of tubular packages comprising an oscillating and reciprocating conveyor, means for feeding the packages of yarn to the conveyor, a pair of resilient members disposed on each side the path of travel of the conveyor, the proximate faces of said members being in spaced relation to each other and facing each other, means for actuating the conveyor to move a package of yarn between the resilient members, and means for moving the members toward each other to engage and apply pressure to the opposite ends of the yarn package simultaneously, the conveyor serving as means for ejecting the crushed yarn package from the apparatus.

7. Apparatus for upsetting the opposite ends of packages of yarn usually mounted on a tube which comprises a reciprocating and oscillating conveyor having pockets therein and means for feeding packages of yarn to the pockets in the conveyor, a pair of cup-shaped members, there being one member mounted on each side of the path of travel of the yarn packages, means for moving the cup-shaped members toward each

other to engage the opposite ends of a package on the conveyor and to simultaneously apply pressure to the opposite ends of the package, means for lowering and retracting the conveyor and again elevating the conveyor to engage a plurality of packages of yarn and position the same in the pockets of the conveyor and to move a succeeding package of yarn between the cup-shaped members for engagement by the cup-shaped members and at the same time discharging a previously crushed package of yarn from between the cup-shaped members.

8. Apparatus for upsetting the opposite ends of packages of yarn usually mounted on a tube which comprises a reciprocating and oscillating conveyor having pockets therein, means for feeding packages of yarn to a position where they will be placed in the pockets in the conveyor, a pair of resilient cup-shaped members mounted on each side of the path of travel of the yarn packages, means for moving the cup-shaped members toward each other to engage the opposite ends of a package on the conveyor and to simultaneously apply pressure to the opposite ends of the packages, means for lowering and retracting the conveyor and again elevating the conveyor to engage a plurality of packages of yarn and position the same in the pockets of the conveyor and to move a succeeding package of yarn between the cup-shaped members for engagement by the cup-shaped members and at the same time discharging a previously crushed package of yarn from between the cup-shaped members.
